RAILWAY TRAFFIC CONTROLLING
APPARATUS

Charles W. Failor, Forest Hills Borough, Pa., assignee to The Union Switch & Signal Company, Swissvale, Pa., a corporation of Pennsylvania

Application June 29, 1931, Serial No. 547,511
Renewed August 15, 1933

24 Claims. (Cl. 246—33)

My invention relates to railway traffic controlling apparatus for utilizing periodically interrupted or coded current in wayside circuits for controlling either or both wayside signals and train carried cab signals, and more particularly it relates to apparatus for utilizing coded current for the control of signal systems that govern traffic in both directions on a stretch of railway track.

10 I will describe certain forms of apparatus embodying my invention, and will then point out the novel features thereof in claims.

The accompanying Figs. 1^a and 1^b when placed end to end with Fig. 1^a on the left constitute a 15 diagrammatic view showing one form of apparatus embodying my invention when applied to an absolute permissive block signaling system. The Figs. 2^a and 2^b when placed side by side with Fig. 2^a on the left constitute a diagrammatic view showing 20 a form of apparatus embodying my invention when applied to an overlap signaling system for a stretch of single track railway. Fig. 3 is a diagrammatic view showing a feature of the system as disclosed in Figs. 1^a and 1^b, while the Fig. 4 25 is a similar diagram showing the same feature as used in the system of Figs. 2^a and 2^b.

In describing my invention I shall assume the left-hand end of each figure to be west and the right-hand end to be east, and I shall speak of a 30 train traveling from the right to the left as a westbound train and one traveling from the left to the right as an eastbound train.

In the following description, reference is made to the accompanying drawings wherein like characters of reference designate corresponding parts, the numeral 1 being prefixed to the reference character when the part is associated with westbound traffic and the numeral 2 being prefixed to the reference character when the part is associated with eastbound traffic, while an exponent 35 is added also to the reference character to designate the location of the part.

Referring first to Figs. 1^a and 1^b, the reference characters 1 and 2 designate the traffic rails of a 40 stretch of railway over which traffic moves in both directions and which includes the passing sidings PS and PS1.

The only wayside signals shown in this absolute permissive block system correspond to the 45 head block or leaving signal at each passing siding. The entrance signal at each siding and all intermediate signals are made phantom signal locations. The head block signal 1S^E governs westbound traffic leaving the siding PS for the siding PS1. The signal 2S^A governs eastbound

traffic leaving the siding PS1, while the signal 2S^F governs eastbound traffic leaving the siding PS. These wayside signals may be of any standard type and are here shown as light signals. The top light of each of these wayside signals when displayed indicates that a clear traffic condition exists to the next passing siding. The center light of each signal is the absolute signal and when used alone displays a stop signal indicating the approach of an opposing train. The bottom signal light of each of the wayside signals is the permissive signal and when displayed in combination with the center light permits a second train to follow a first train from a passing siding without waiting until the first train has reached the next siding. As stated above, the remaining wayside signals, indicated on the drawing by dotted lines, are phantom signal locations. The signal conveyed at each of these points to a passing train is in this instance to be in the form 20 of a continuous cab signal as will be more fully pointed out later. It will be understood of course that other types of wayside signals could equally as well be employed and as a matter of fact, wayside signals could be located in each of the phantom signal locations if it seemed desirable to do so 25 without departing from the scope of my invention.

The traffic rails 1 and 2 are divided by the usual insulated rail joints 3 into the track sections A—B, B—C, C—D, D—E and E—F, although other arrangements of track sections for this stretch of railway could be employed equally as well. Each track section is provided with the well known conventional direct current track circuit which includes a battery 4 connected with the rails at one end of the section and a direct current relay TR connected to the rails to the opposite end of the section. Coded alternating current is superimposed on the direct current 30 track circuit at both the battery and relay ends of the section for controlling cab signal equipment carried on a train in the manner well understood by all familiar with the art. Looking at the track section B—C of Fig. 1^a for illustration, the secondary 5 of a track transformer 1T^B is included in the track leads in series with the battery 4, there being also included the usual current limiting resistor 6 and an impedance coil 7. 35 At the relay end of the section B—C, the secondary 8 of a second track transformer 2T^C is connected to the rails in parallel with the winding of the track relay 1TR^C through a resistance 9. By the means of these track transformers coded 40 45 50 55

alternating current is supplied to the traffic rails in a manner about to be described.

As the general construction of the apparatus at the head block signal location is in all instances the same, a detailed description of the equipment for the location A is submitted as being typical of all such locations. Energy for the operation of the apparatus at the location A is supplied from a line transformer L, the primary 10 of which is connected to a transmission line indicated by the two line wires 11 and 12 which are constantly supplied with alternating current of any convenient commercial frequency such as sixty cycles per second by a source not shown in the figures. The bus wires BX110 and CX110 are permanently connected to the two terminals of the secondary 13 of the transformer L and energy for the various circuits is obtained from these bus wires. To the bus wires BX110 and CX110 is connected the primary 14 of a transformer T^A , the secondary 15 of which is in turn connected to the input terminals of a full wave rectifier 16. The output terminals of the rectifier 16 are connected to a storage battery 17 and thus it follows that the storage battery is continuously trickle charged by the alternating current supplied to the rectifier 16. The terminals of the storage battery are connected to the bus wires B10 and C10 which distribute direct current to certain of the circuits at this location. This storage battery 17 also acts as a standby source of supply for all the circuits in the event of a failure of the alternating current transmission line.

At location A, there is provided a transformer VP, the primary 18 of which is permanently connected to the bus wires BX110 and CX110. The transformer VP has two secondary windings 19 and 20; the secondary 19 supplies current to the winding of a "power-off" relay GZR, while the secondary 20 is connected to the front contacts 27 and 32 of the relay GZR through which alternating current is normally supplied to the operating circuits of the signal $2S^A$.

The operating circuit for the clear signal lamp 26 of the signal $2S^A$ extends from the bus wire BX10 through the front contact 27 of the relay GZR, wire 28, front contact 29 of a slow acting line relay $2H^A$ to be described later, wire 30, signal light 26, wire 31 and front contact 32 to the bus wire CX10. The circuit for the absolute signal lamp 33 extends as before traced from the bus wire BX10 to the wire 28 and thence by the back contact 34 of the relay $2H^A$, wire 35, signal light 33 and back to the bus wire CX10. The operating circuit for the permissive signal light 39 branches from the wire 35 along the wire 36, front contact 37 of a stick relay $2V^A$ to be later described, wire 38, permissive signal light 39 and then back to the bus wire CX10. With the relay GZR deenergized as it will be in the case there is a loss of alternating current then these operating circuits for the signal $2S^A$ are connected to the terminals of the storage battery 17 by means of the back contacts 40 and 41 of relay GZR and current for operating signal $2S^A$ is then supplied by battery 17. The function therefore of the power-off relay GZR is to transfer the connection of the signal operating circuits from the transformer secondary 20 to the storage battery 17 in case of an interruption in the supply of alternating current from the line transformer L.

The terminals of a second power-off relay ZR are permanently connected to the bus wires BX110 and CX110 and the function of this power-off

relay is to render a local tuned alternator TG active to supply alternating current to certain of the circuits in the event there is a loss of the normal supply of alternating current from the transmission line.

The tuned alternator TG may take different forms but a preferred form is that of a vibrating relay and transformer combination. The armature 107 of the relay M is normally biased to a middle position as shown in Fig. 1^a and is mechanically tuned by the biasing and by the proportion of its parts to a given natural period of vibration. With the winding 21 of the relay M supplied with direct current, the armature 107 vibrates at its natural period due to the fact that its energizing circuit is intermittently opened by its own contact 157. As the armature 107 thus vibrates it makes contact alternately once each cycle with the contacts 108 and 109. These contacts 108 and 109 are connected to the outside terminals of the primary 110 of a transformer 22, the center tap of which is permanently connected to the negative terminal of the storage battery 17. With the relay ZR deenergized the back contact 75 is closed to connect the armature 107 to the positive terminal of the battery 17, and the winding 21 is energized causing armature 107 to vibrate. As the armature 107 vibrates it alternately engages 108 and 109 and an impulse of current is caused to alternately flow in the two halves of the primary 110 of the transformer 22 with the result that an alternating current is induced in the secondary 111. A condenser 112 may be connected across the terminals of the primary 110 if so desired. The mechanical tuning of the armature 107 is made such that the alternating current supplied by the secondary 111 has a frequency substantially equal to that of the current of the transmission line. As long as the relay ZR is energized, the bus wire BX110 is connected to a control circuit supplied from BX110 and CX110 and to be fully described later, at the front contact 66, and the tuned alternator TG is inactive. The deenergizing of the relay ZR not only closes its back contact 75 the connection to the relay M from the storage battery 17, but it also transfers the above mentioned control circuit from the bus wire BX110 to one terminal of the secondary 111 of the transformer 22 by opening contact 66 and closing back contact 113. As the opposite terminal of the secondary 111 is permanently connected the bus wire CX110 the transformer 22 now supplies alternating current to the control circuit. Thus the function of the power-off relay ZR is to render active the local tuned alternator TG in the case of a loss of power from the alternating current transmission line and to transfer the connection of the control circuit from the bus wire BX110 to the output of the tuned alternator TG which then supplies this control circuit with alternating current at substantially the same frequency as that of the normal supply of current derived from the transmission line.

Two code transmitters CT and CT1 are provided at the location A, the motor element of each of which is permanently connected to the storage battery 17 as is evident from an inspection of Fig. 1^a, and thus these code transmitters are continuously active. These code transmitters are to be of any of the standard type commonly used in code systems, and are here shown as of the direct current type and in this description it will be considered that each code transmitter CT of the system operates its contact members at a

rate of one hundred eighty times per minute, and that each code transmitter CT1 operates its contact member at a rate of eighty times per minute. It will be understood, however, that other rates of operation could equally as well be employed without departing from the scope of my invention.

Associated with each wayside signal is a slow acting relay H which for the signal 2S^A at the location A, is designated by the reference character 2H^A. This relay is preferably of the direct current neutral type having slow release characteristics and also of a design that is slow to pick up as energy is applied to its winding. The terminals of the winding of this relay are permanently connected to the output terminals of a full wave rectifier 42. As the input terminals of the rectifier 42 are permanently connected to the terminals of the secondary 43 of a transformer 2U^A, it follows that with alternating current supplied to the primary 44 of transformer 2U^A, the relay 2H^A is energized, and due to its slow release characteristics, it will retain its energized position during the open circuit period when the alternating current supplied to the primary 44 is coded. The supply of alternating current for energizing the primary 44 of the transformer 2U^A is derived from the location at the opposite head block signal which in this instance is location E at the passing siding PS. This control circuit can be traced from the bus wire BX110 at location E through the front contact 45 of the power-off relay ZR at location E, back contact of the contact member 46 of the code transmitter CT, front contact 47 of the track relay 1TR^E of the section D—E, wire 48, back contact 49 of the stick relay 1V^E, line wire 50, front contact 51 of the track relay 2TR^C for the section C—D, wire 56, front contact 52 of track relay 1TR^C for the section B—C, line wire 53, front contact 54 of the track relay TR^A for the section A—B, primary winding 44 of the transformer 2U^A and return line wire CX110 to the bus wire CX110 at the location E. It follows then that the line relay 2H^A is energized only when all the track sections between the two passing sidings PS and PS1 are unoccupied and that due to the slow releasing characteristics of the relay, it remains energized even when the alternating current supplied to the above traced circuit is coded by the code transmitter CT.

This same circuit that I have just traced for energizing the line relay 2H^A that governs the wayside signal 2S^A, also supplies coded alternating current to the track circuit of each of the track sections A—B, B—C and C—D. Referring to the location D of Fig. 1^A, the primary 55 of the track transformer 2T^D is connected across the line wire 50 and the return line wire CX110. The primary 57 of the track transformer 2T^C for the section B—C is connected across the wire 56 and the return wire CX110, while likewise the primary 58 of the track transformer 2T^B for the section A—B is connected across the wire 53 and the return wire CX110. Thus this control line circuit not only supplies current to the relay 2H^A, which governs the operation of the wayside signal 2S^A, but it also supplies the traffic rails of each of the sections A—B, B—C and C—D with coded alternating current which is adapted to control cab signal equipment of the continuous control type of eastbound trains traveling these track sections. It follows then that the line relay 2H^A for the signal 2S^A is energized by the coded alternating current supplied

at the location E, to the line circuit that supplies coded energy to the traffic rails of intervening track sections governed by signal 2S^A.

To permit following eastbound train movements past the head block signal 2S^A, there is provided at the location A, a stick relay 2V^A. The energizing circuit for the stick relay 2V^A extends from the positive bus wire B10 through the back contact 59 of the track relay TR^A, front contact 60 of the line relay 2H^A, winding of the relay 2V^A and to the negative bus wire C10. Thus when an eastbound train passes the signal 2S^A and shunts the track relay TR^A the stick relay 2V^A will pick up before the line relay 2H^A releases due to the slow releasing characteristics of that relay. After the stick relay 2V^A is once energized it is retained energized by either of its two stick circuits both of which include its own front contact 61. One of these stick circuits branches from the contact 61 directly to the back contact 59 of the track relay TR^A, while the second stick circuit extends from the contact 61 through the back contact 62 of the relay 2H^A. As the circuit for the permissive signal light 39 is closed at the front contact 37 of the stick relay 2V^A, it follows that any second or following eastbound train will receive a permissive signal indication at the signal 2S^A whereby it may follow the first eastbound train without waiting for the first train to reach the passing siding PS.

The apparatus and circuits at the locations E and F are each similar to that just described for the location A except that at location E the apparatus controls traffic in the opposite direction and it is thought not necessary to point out these circuits in detail. It is desired, however, to refer to the control circuit for the relay 1H^E at the location E which governs the signal 1S^E. This relay is similar to the relay 2H^A at the location A, and is governed by current supplied by the secondary 63 of the transformer 1U^E through a rectifier 64. The primary 65 of the transformer 1U^E receives its energy from the location A over a control circuit that may be traced from the bus wire BX110 at the location A through the front contact 66 of the power-off relay ZR, back contact of the contact member 24 of the code transmitter CT, front contact 67 of the track relay TR^A, back contact 68 of the stick relay 2V^A, line wire 69, front contact 70 of the track relay 1TR^C, wire 71, front contact 72 of the track relay 2TR^C, line wire 73, front contact 74 of the track relay 1TR^E, primary winding 65 of the transformer 1U^E, and return wire CX110 to the bus wire CX110 at the location A. This control circuit also supplies coded alternating current to the track circuits of each of the sections B—C, C—D and D—E. Referring to the location E, the primary 76 of the track transformer 1T^B is connected across the wire 69 and the return wire CX110. The primary 77 of the track transformer 1T^C of section C—D is connected across the wire 71 and the return wire CX110, while the primary 78 of the transformer 1T^D for the section D—E is connected across the wire 73 and the return wire CX110. Thus this control circuit which governs the signal controlling relay 1H^E also supplies coded alternating current to the traffic rails of the sections B—C, C—D and D—E for the control of cab signal equipment of westbound trains. In other words the control circuit which governs the westbound wayside signal also supplies the traffic rails of the sections governed by that signal with cab signal energy.

Referring to the track section D—E, the east end of its traffic rails is supplied with coded alternating current by means of the track transformer 2T^E. The primary 79 of the track transformer 2T^E normally receives its energy from the location F at the east end of the passing siding PS in the following manner. Starting at the bus wire BX110 at location F there extends a circuit through the front contact 80 of the power-off relay ZR at that location, front contact of the contact member 81 of the code transmitter CT, front contact 82 of the signal relay 2H^F, wire 83, primary 84 of an insulating transformer 1T^F and wire 85 to the bus wire CX110. The secondary 86 of the insulating transformer 1T^F is connected to the primary 79 of the transformer 2T^E by wire 87, front contact 88 of the track relay 2TR^E, primary 79, and wires 89 and CX110A to the opposite terminal of the primary 86.

In the event the line relay 2H^F is deenergized then eighty code alternating current is supplied to the transformer 1T^F through the contact member 90 of the eighty code transmitter CT1 at the location F and the back contact 91 of the line relay 2H^F and this eighty code current is then supplied by the secondary 86 of the transformer 1T^F to the track transformer 2T^E of the section D—E. It is to be noted that by providing the insulating transformer 1T^F it is possible to cut the common line wire CX110 at this location. In the event the track relay 2TR^E is shunted due to the fact of a train occupying the section E—F, then the primary 79 of the track transformer 2T^E is supplied with eighty code energy from the bus wire BX110 at the location E through the back contact of the contact member 92 of the eighty code transmitter CT1 at the location E and the back contact 93 of the track relay 2TR^E. Thus as long as clear traffic conditions exist east of the passing siding PS, that is, to the east of the wayside signal 2S^F, and the signal governing relay 2H^F is energized, one hundred eighty code alternating current is supplied to the track section D—E, which is the first section to the west of the passing siding, to establish the one hundred eighty code condition of the cab signal equipment of eastbound trains. If traffic conditions to the east of the signal 2S^F are such as to deenergize the line relay 2H^F so that this signal indicates stop then eighty code alternating current is supplied to the track section D—E to effect an eighty code condition of the cab signal of an eastbound train traveling that section. Furthermore in the event the track section E—F adjacent the passing siding PS is occupied by a train then eighty code current is also supplied to the section D—E for eastbound trains.

In connection with westbound traffic a similar arrangement is provided for the track section to the east of each passing siding, such as the section A—B and the section to the right of the location F. Coded alternating current is supplied to the west end of these sections by the track transformers 1T^A and 1T^F, respectively, and I shall refer to the transformer 1T^F in describing the method of applying coded current to these sections for governing westbound traffic. The primary 95 of transformer 1T^F is supplied with alternating current by a circuit extending from the bus wire BX110 at the location E through the contact 45 of the relay ZR, front contact of the contact member 96 of the one hundred eighty code transmitter CT, front contact 97 of the line relay 1H^E, wire 98, front contact 99 of the track

relay 2TR^E, wire 100, primary 95, wire CX110A to the bus wire CX110 at the location E. In the event the line relay 1H^E is deenergized, then the above circuit to the primary 95 is supplied with eighty code current through the contact member 101 of the code transmitter CT1 at the location E, along wire 102, back contact 103 of the line relay 1H^E and hence as before traced. Again in the event that track relay 2TR^E is down, eighty code current is supplied to the primary 95 through the contact member 101 of the code transmitter CT1 and the back contact 104 of this track relay. Thus with clear traffic conditions to the west of the passing siding PS, the track section to the right of location F is supplied with one hundred eighty code energy for westbound traffic while when the traffic conditions are such as to deenergize the line relay 1H^E, eighty code is supplied to the track section to the right of location F for governing westbound traffic.

The track section adjacent the passing siding PS, that is, the section E—F, has coded alternating current supplied to its traffic rails at the west end of the section by a transformer 1T^E whose primary 105 is arranged in parallel with the circuit feeding the primary 95 of the track transformer 1T^F as will be observed by an inspection of Fig. 1^b. The east end of the section E—F is fed by the track transformer 2T^E whose primary 106 is in parallel with the primary 84 of the transformer 1T^F. Thus this section E—F adjacent the siding has its rails supplied at each end with either one hundred eighty or eighty code energy depending upon the condition of the signal governing relay H at the respective end of the siding, one hundred eighty code under clear traffic conditions when the relay is energized and eighty code if traffic conditions are such that the line relay is deenergized.

To sum up thus far the apparatus of Figs. 1^a and 1^b supplies coded alternating current to an eastbound control circuit and to a westbound control circuit. The east bound control circuit not only controls the east bound wayside signals but also supplies the traffic rails of the track sections with coded energy adapted to control train carried cab signals of eastbound trains. Likewise the westbound control circuit not only controls the westbound wayside signals but also supplies coded current to the traffic rails of the track sections for governing the cab signals of westbound trains. While the normal supply of power is derived from an alternating current transmission line there is provided at each location standby equipment which is automatically rendered active to supply the control circuits with proper energy in the event of a failure of the transmission line.

In describing the operation of the apparatus of Figs. 1^a and 1^b, I shall assume an eastbound train occupies the track section to the west of the location A and that all track sections to the location E are unoccupied. The control line circuit extending from the location E to the location A is complete and thereby supplies one hundred eighty code to the east end of the sections C—D, B—C and A—B through the transformers 2T^D, 2T^C and 2T^B, respectively, and to the primary 44 of the transformer 2U^A to energize the line relay 2H^A. With the relay 2H^A energized, then a clear signal indication is displayed by the signal 2S^A permitting the train to advance into the section A—B. As the train travels east through each of the successive track sections, one hundred eighty code alternating current is applied to the rails

at the east end of each section to establish the one hundred eighty code condition of the cab signal equipment. As the train passes the signal $2S^A$, the stick relay $2V^A$ will be picked up by the closing of its energizing circuit at the back contact 59 of the track relay TR^A during the interval the slow releasing characteristics of the relay $2H^A$ still retain that relay in the energized position. With the relay $2V^A$ once energized, it is retained energized by its stick circuit until the relay $2H^A$ is again energized which will not occur until this eastbound train has vacated the section D—E. With the stick relay $2V^A$ up to close the front contact 37, the circuit to the permissive signal light 39 is closed causing thereby a permissive signal to be displayed by signal $2S^A$. Should therefore a second eastbound train approach the signal $2S^A$ while the first train still occupies the stretch of track between the two passing sidings, a permissive wayside signal is displayed to this second train permitting it to follow the first train through this stretch of track. As the first eastbound train advances through the successive track sections, the supply of coded alternating current to the sections to the rear of the train is cut off at the successive track relays. Thus as a second or following train advances past the permissive wayside signal, there is available no one hundred eighty code energy for the cab signal equipment of this second train.

Going back again to where the first eastbound train occupies the section to the left of location A, as soon as this train enters the section A—B and shunts the track relay TR^A , the westbound control circuit, that supplies coded current to the west end of the successive track sections and which also governs the signal relay $1H^E$ at the location E, is opened at the contact 67 of the track relay TR^A . The deenergizing of the relay $1H^E$ causes the opposing wayside signal $1S^E$ to display a stop signal for westbound traffic, and the discontinuing of coded current to the west end of the successive track sections deenergizes the cab signal equipment of any westbound train entering this stretch of track. As the line relay $1H^E$ becomes deenergized, then eighty code current is supplied by the westbound transformers $1T^E$ and $1T^F$ to the section E—F and the section to the east of location F, respectively. Any westbound train approaching the signal $1S^E$ at this time will therefore have its cab signal equipment influenced by eighty code track current in the section E—F and the section to the east of F.

In the event there is a westbound train approaching the siding PS as the eastbound train approaches the siding PS from the west, there will be supplied to the east end of the track section D—E eighty code current so that an eighty code condition is established for the cab signal equipment of the eastbound train as it approaches the siding PS,—that is, as it approaches the head block signal $2S^F$ which now displays a stop indication an eighty code condition of its cab signal prevails. The operation of the apparatus for a westbound train traveling from the siding PS to PS1 is similar to that just described for an eastbound train.

In Figs. 2^a and 2^b there is disclosed my invention applied to an overlap signal system for a stretch of single track railway that includes a passing siding PS2. The track rails 1 and 2 of this stretch of railway are divided by the usual insulated rail joints into the track sections A—A₁, A₁—B, B—C, C—C₁, C₁—D, D—E and E—E₁. The wayside signals to be used in this

overlap system may be of any of the standard type and are here shown by symbol as of the semaphore type. The entrance signals $2S^A$ and $1S^B$ at each end of the passing siding PS2 are three position signals capable of displaying a clear, caution and stop indication. The head block signals $1S^A$ and $2S^B$ and the intermediate signals $2S^D$ and $1S^E$ are each two position signals capable of displaying a clear or stop indication while the signal $1S^C$ acts as a distant signal for the signal $1S^B$ and is adapted to display a clear or caution indication.

Each track section is provided with the conventional direct current track circuit, the same as described for Figs. 1^a and 1^b. The secondary of a track transformer is connected in series with the battery leads at the battery end of each section while the secondary of a second track transformer is connected in parallel with the winding of the track relay at the relay end of each track section for the purpose of superimposing coded alternating current on this direct current track circuit, the same as described in connection with the apparatus of Figs. 1^a and 1^b.

The normal source of the alternating current is obtained from an alternating current transmission line designated by the line wires 177 and 158, which are constantly connected to a source of alternating current, not shown in the figures. The operating circuits of each wayside signal are supplied in this instance with direct current derived from a primary battery 140, which of course could be replaced by a trickle charged storage battery, the same as shown in Figs. 1^a and 1^b, if it seemed desirable to do so. The battery 140 acts also as a standby source of energy in the case of an interruption of service of the transmission line. The power-off relay ZR acts to connect the local tuned alternator TG to the battery 140 and to transfer the connection for the control line circuit from the bus wire BX110 to the output of the tuned alternator in a manner similar to that described for Figs. 1^a and 1^b. Code transmitters CT and CT1 are provided at certain locations to code the alternating current supplied to the control line circuit and these code transmitters are constantly active by having their winding permanently connected to the battery 140 at that location.

Furthermore, the principle of energizing the wayside signal governing relay H and supplying cab signal energy to the traffic rails over the same control line circuit is used in this overlap system, the same as was described in connection with the absolute permissive block system of Figs. 1^a and 1^b. Looking at the line relay $2H^A$ that governs the operating circuits for the signals $2S^A$ and which is energized through a rectifier 142 by current induced in the secondary 141 of the associated transformer $2U^A$, we find that the control circuit extends from the bus wire BX110 at the location A through the contact 124 of the power-off relay ZR, back contact of the contact member 123 of the code transmitter CT, line wire 122 to the location B, hence through controller 120 operated by the mechanism of the signal $2S^B$ as indicated by a dotted line and closed only when the signal indicates clear, front contact 119 of line relay $2H^B$, front contact 118 of the track relay $2TR^B$, wire 126, front contact 117 of the track relay $1TR^B$, line wire 116, front contact 115 of the track relay $2TR^A$, primary 114 of the transformer $2U^A$ and to the bus wire CX110. The primary 125 of the track transformer $2T^B$ for the section A₁—B is connected across the wire 126.

and the return wire CX110, and likewise the primary 127 of the transformer 2T^{A1} is connected across wire 116 and the return wire CX110, so that both of these track transformers are supplied with coded alternating current over the same circuit that controls the signal controlling relay 2H^A. Looking next, at the signal governing relay 2H^B at the location B of Fig. 2^a, we find that the control circuit for this relay extends from the bus wire BX110 at the location D through the front contact 129 of the power-off relay ZR, back contact of the contact member 130 of the code transmitter CT, contact 131 of the relay 132, front contact 133 of track relay 2TR^P, wire 134, front contact 135 of track relay 1TR^P, line wire 136, front contact 137 of the track relay TRC, wire 138, front contact 139 of the track relay 2TR^B, primary 128 and to the bus wire CX110 at location D by the common line wire CX110. It will be noted that in this instance, the track transformers 2T^D, 2T^{C1} and 2T^C for the sections C1—D, C—C1 and B—C, respectively, are also supplied with coded alternating current by this same control line circuit that has just been traced for the relay 2H^B. It is thought not necessary to trace in detail each individual control circuit for all the signal governing relays of Figs. 2^a and 2^b and to point out in detail how in each case the control circuit also supplies coded alternating current to the track sections in advance of the signal governed by the relay. The two control circuits traced above for the relays 2H^A and 2H^B, respectively, will serve to illustrate the principle by which I prefer to control, by a single circuit, both the wayside signal and the supply of cab signal energy to the traffic rails of the stretch of track governed by that signal.

In describing the operation of the apparatus of Figs. 2^a and 2^b, I shall assume that a westbound train is approaching the signal 1S^E, that is, a westbound train occupies the track section E—E1, while the remaining track sections are all unoccupied. Previous to this westbound train entering the section E—E1, the supply of current to the primary 144 of the insulating transformer 1T² was cut off. It will be understood that the supply of coded alternating current to the primary 144 of the insulating transformer 1T² is governed by traffic conditions to the east of the location E1 in a manner similar to that by which all the U transformers are controlled, and which is also similar to that described for the insulating transformer used in Figs. 1^a and 1^b. The insulating transformer 1T² passes to the circuit fed by its secondary 159 alternating current of the same code as that impressed upon the alternating current supplied to its primary 144. It follows then that this westbound train will have set up a traffic condition before it reaches the section E—E1 that deprives the primary 144 of current so that in turn the transformer 2UP is deprived of power as is also the track transformer 2T^E. The function of the insulating transformer is that of permitting the return line wire CX110 which is common to both east and westbound control circuits, to be cut at such locations as may seem desirable. The signal control relay 2H^P is thus deenergized in response to the approach of this westbound train so that the signal 2S^D indicates stop, and also no cab signal current is supplied to the east end of the section D—E for influencing cab signal equipment of eastbound trains in that section.

The shunting of the track relay TR^E by the 75 westbound train entering the section $E-E1$ opens

the circuit to the relay 132 at the front contact 145. The deenergizing of the relay 132 in turn cuts off at its front contact 131, the supply of coded alternating current to the control circuit leading to the transformer 2UB and to the track transformer located at the east end of each intervening track section between the signals 2SB and 2SD. The depriving of this control circuit of coded alternating current deenergizes the relay 2HB to set the head block signal 2SB at stop and 10 to discontinue the cab signal energy for all east-bound trains leaving the passing siding PS2. With the relay 2HB down, then one hundred eighty code energy is cut off at its front contact 119 from the control circuit leading to the transformer 2UA associated with the relay 2HA. As 15 the relay 2HB drops, it closes at its back contact 146 a connection so that this control circuit to the transformer 2UA is now supplied with eighty code energy from the code transmitter CT1 at 20 the location A, to thereby retain the relay 2HA energized and to supply the east end of the sections A—A1 and A1—B with eighty code energy 25 to effect an eighty code condition upon the cab signal equipment of any eastbound train entering either of these sections to the rear of this stop signal 2SB. Although the relay 2HA is thus retained energized, the wayside signal 2SA is 30 however moved to its caution position inasmuch as its clear operating circuit receives energy from the battery 140 at the location B. This operating circuit normally extends from the positive terminal of the battery 140 at the location B through the front contact 148 of the relay 2HB which is now deenergized, and the circuit controller 149 operated by the mechanism of the signal 2SB and which controller is closed only 35 when the signal 2SB is in the clear position, thence by the line wire 150, front contact 151 of the relay 2HA, signal mechanism 2SA and return 40 wire CX110 to the negative terminal of the battery 140 at the location B. As the signal 2SA assumes the caution position, the controller 152 operated by the mechanism of this signal is shifted from its 90° position to its 45° position, 45 so that the track transformer 2TA is now supplied with eighty code alternating current from the code transmitter CT1 in place of one hundred eighty code energy from the code transmitter CT. This circuit for supplying eighty 50 code current to the transformer 2TA extends from the bus wire BX110 through the contact 124, front contact of the contact member 160 of the code transmitter CT1, wire 161, controller 152, contact 162 of the relay 2HA, primary of the 55 track transformer 2TA and to the bus wire CX110. Also as the signal 2SA assumes the caution position, the circuit controller 166 which is closed only when the signal 2SA is in the clear position 60 is opened so that the line wire 167 extending to a distant signal for the signal 2SA is no longer connected to the positive terminal of the battery 140 with the result that this distant signal will be set at caution. It is here pointed out that this distant signal for the signal 2SA will be controlled 65 in the same manner as is shown for the distant signal 1SC.

Thus we see that the westbound train in the section E—E1 holds both the opposing eastbound signals $2S^D$ and $2S^B$ at stop and the signal $2S^A$ 70 and its distant signal at caution by depriving the control line circuit for each of the signals $2S^D$ and $2S^B$ of power, and by opening the clear operating circuits for the signal $2S^A$. The depriving of the control circuits for the signals $2S^D$ and 75

2S^B of power also leaves the track transformer at the east end of each intervening section without code energy by which to influence cab signal equipment on eastbound trains. At the same time, that the signal 2S^A and its distant signal are set at the caution position, the track transformer located at the east end of the track section governed by these signals is supplied with eighty code alternating current to establish an eighty code condition of the cab signal equipment of eastbound trains. In other words, the opposing overlap provided by the usual overlap systems for wayside signals is also provided by this system disclosed in Figs. 2^a and 2^b.

As the westbound train in the section E—E1 advances through this section, the signal 1S^E displays a clear signal and the rails of the section are supplied with one hundred eighty code alternating current to establish the corresponding condition of the cab signal equipment. Assuming the train to continue west past the signal 1S^E and proceed west to the passing siding PS2, the traffic rails of each successive track section are supplied with one hundred eighty code energy and the wayside signals 1S^B and 1S^A display a clear wayside signal indication. As the westbound train enters the section D—E and shunts the track relay 2TR^D, the supply of coded alternating current is cut off from the transformer 1U^E at the front contact 169 so that the signal relay 1H^E is deenergized and the signal 1S^E caused to assume the stop position. As the control circuit by which code energy for the westbound traffic is applied to the rails of the successive track sections is controlled through the contacts 153, 154 and 155 of the successive track relay, respectively, the rails to the rear of the westbound train are left without code energy and any following westbound train passing the stop signal 1S^E will be left without control for its cab signal equipment.

In the event there is another train occupying either of the sections A—A1 or A1—B at the passing siding PS2 as this westbound train advances from the section E—E1, then the westbound signal 1S^B is at stop and the signal 1S^C at caution and eighty code energy is supplied to the track transformer 1T^B inasmuch as the controller 156 is now at the 0° position where a connection is made to the wire 147 leading to the back contact of the contact member 160 of the eighty code transmitter CT1 at the location A.

If the section to the left of location A is occupied by a train so that its track relay 1TR^A is shunted, both westbound signals 1S^A and 1S^B are at stop and the signal 1S^C is at caution. With the track relay 1TR^A down, then no code energy is supplied to either of the track transformers 1T^A and 1T^{A1}, while eighty code current is supplied to the track transformer 1T^B, the same as pointed out above. The westbound train under this traffic condition receives a caution wayside signal at 1S^C and an eighty code condition of its cab signal equipment in the section E—C, and no code for its cab signal in the sections A—A1 and A1—B in the event that it continues past the stop signal 1S^B.

If, however, the traffic condition that holds the signal 1S^A at stop by deenergizing its control relay 1H^A is further to the west than the first section to the left of location A so that the track relay 1TR^A is energized and its front contact 163 closed, then the signal controlling relay 1H^B for signal 1S^B is energized inasmuch as its associated transformer 1U^B is supplied with eighty code en-

ergy. The circuit for supplying this eighty code current starts from BX110 at location A and extends through the front contact 160 of the code transmitter CT1, wire 161, controller 121, front contact 163 of track relay 2TR^A, front contact 165 of the track relay 1TR^B, primary of transformer 1U^B and common line wire CX110 to the bus wire CX110 at location A. The clear operating circuit for the signal 1S^B, however, is open at the controller 168 operated by the mechanism of signal 1S^A so that the signal 1S^B displays caution even though its control relay 2H^B is energized. Under this traffic condition, the westbound train receives one hundred eighty code for its cab signal equipment up to the caution signal 1S^B but after it passes this signal, it then is affected by eighty code current and if it advances past the stop signal 1S^A, its cab signal equipment is without code energy.

The operation of the apparatus for an eastbound train is similar to that just described for a westbound train and it is thought not necessary to describe it in detail. However, it is desired to point out that with an eastbound train advancing past the signal 2S^B under clear traffic conditions, the signal 2S^B is set at stop and each of the successive track sections to the rear of the train as it advances east to the signal 2S^D is left without code energy. It is not until the eastbound train vacates the section E—E1 so that the track relay 2TR^E picks up, and in turn the relay 132 becomes energized, that the control circuit to the transformer 2U^B at the signal 2S^B and to the intervening track circuits is again supplied with coded alternating current. To sum up the operation of the apparatus of Figs. 2^a and 2^b, the overlap protection provided by the usual overlap wayside signal systems for both opposing and following train movements is obtained for both the wayside signals and the one hundred eighty code condition of the cab signal energy. A caution wayside signal and an eighty code condition of the cab signals are provided at a passing siding in order to permit trains to safely approach each other at siding locations. Also the control of the wayside signal and the supply of the coded track circuit current is accomplished by a single line control circuit.

Another feature of my invention resides in arranging the several control circuits supplying code energy to the H relays and to the several track circuits so that the circuits fed by any one code transmitter are substantially equally divided between front and back contacts which are alternately closed. The result of such an arrangement is that the current delivered by the source to these circuits has its maximum instantaneous value minimized. In commercial systems where local tuned alternators are called upon to supply the current a division of the control circuits between front and back contacts of the code transmitter is especially desirable, for by keeping the maximum instantaneous power demand low a more reliable operation of tuned alternators of a type that require for their operation but a small amount of power from the standby battery can be obtained. Fig. 3 shows in outline, the arrangement that is used in the system of Figs. 1^a and 1^b. The contact member 23 of the code transmitter CT at the location A supplies through its front contact the circuits to the west of the location A, while the contact member 24 which is operated in step with the contact member 23, supplies through its back contact, the circuits to the east of the

location A. Again the contact member 96 of the code transmitter CT at the location E supplies through its front contact, the circuits to the east of the location E while the contact member 46 supplies through its back contact, the circuits to the west of location E. In Fig. 4 is shown in diagram the arrangement employed in the system of Figs. 2^a and 2^b. Here the contact member 123 of the code transmitter CT at the location A supplies code energy through its front and back contacts to approximately an equal number of track circuits. Likewise the code transmitter CT at the location D supplies approximately an equal number of track circuits through the front and back contact of its contact member 130. An inspection of Figs. 1^a, 1^b, 2^a and 2^b will disclose that this same arrangement is provided for the code transmitters CT1.

While I have here disclosed my invention applied to only two types of signal systems, it will be apparent from this description that the same principle can equally as well be applied to signal systems for double track railways. The utility of controlling both wayside signals and cab signals over the same line control circuit will be apparent to all those familiar with this class of apparatus.

Although I have herein shown and described only certain forms of apparatus embodying my invention, it is understood that various changes and modifications may be made therein within the scope of the appended claims without departing from the spirit and scope of my invention.

Having thus described my invention, what I claim is:

1. In combination, a stretch of railway arranged into a plurality of track sections, a wayside signal to govern traffic through said stretch, a relay to control the operation of said signal, a track transformer for each of said track sections connected to the traffic rails of the section, a line circuit to control both said relay and said track transformers, and a source of current to supply coded alternating current under certain traffic conditions to the line circuit for energizing said relay and for supplying to the traffic rails of each section current adapted to influence train carried cab signals.

2. In combination, a stretch of railway, a wayside signal to govern traffic through said stretch, a direct current relay to control the operation of said signal, a traffic controlled line circuit for supplying to the traffic rails of said stretch coded alternating current adapted to influence train carried cab signals, and means including a full-wave rectifier responsive to the coded alternating current of said line circuit for energizing said direct current relay and thereby also controlling said wayside signal.

3. In combination, a stretch of railway, a wayside signal to govern traffic through said stretch, a track circuit including the traffic rails of the stretch adapted to control train carried cab signals, a line circuit, a traffic controlled means to supply under clear traffic conditions coded alternating current to said line circuit, means controlled by the line circuit responsive to said coded current for clearing said wayside signal, and means for supplying coded alternating current from said line circuit to the said track circuit for influencing train carried cab signals.

4. In combination, a stretch of railway, a wayside signal to govern traffic through said stretch, a track circuit for the stretch adapted to control train-carried cab signals, a line circuit, a

traffic controlled means to supply under certain traffic conditions to said line circuit a current of a distinctive characteristic, means controlled by the line circuit responsive to said current for operating said signal, and means for supplying current of said characteristic from said line circuit to said track circuit. 5

5. Railway traffic controlling apparatus including, a stretch of railway over which traffic moves in both directions, a wayside signal at each end of the stretch to govern traffic in opposite directions through the stretch, a line circuit for each signal normally supplied with coded alternating current at the end of the stretch opposite the associated signal, a circuit controlling device for each line circuit responsive to coded alternating current for clearing the signal associated with said line circuit, track circuit means responsive to a train entering the stretch at either end of the stretch to discontinue the supply of coded alternating current to the line circuit receiving current at the end of the stretch at which the train enters for setting the associated signal at stop, and means associated with each line circuit to supply coded alternating current from the line circuit to the traffic rails of the stretch to control train-carried cab signals. 20

6. Railway traffic controlling apparatus including, a stretch of railway over which traffic moves in both directions said stretch being divided into a plurality of track sections, a wayside signal at each end of the stretch to govern traffic in opposite directions through the stretch, a line circuit for each signal normally supplied with coded alternating current at the end of the stretch opposite the associated signal, a circuit controlling device for each line circuit responsive to coded alternating current for clearing the signal associated with said line circuit, track circuit means responsive to a train entering the stretch to discontinue the supply of coded alternating current to the line circuit receiving current at the end of the stretch at which the train enters for setting the associated signal at stop, and means associated with each line circuit to supply coded alternating current from the line circuit to the traffic rails of each of the track sections to control train-carried cab signals. 30

7. A signal system for railways including, a stretch of single track between two passing sidings, a wayside signal having a stop condition at each passing siding to govern traffic in opposite directions through the stretch, a line circuit associated with each wayside signal said line circuit normally supplied with coded alternating current at the end of the stretch remote from the signal with which the line circuit is associated, a relay for each line circuit energized in response to the coded current of the associated line circuit for holding in abeyance the stop condition of the associated wayside signal, means associated with each line circuit to supply to the track of the stretch from the line circuit coded alternating current adapted to govern train-carried cab signals of trains travelling in the same direction as that governed by the associated wayside signal, and trackway means responsive to a train entering either end of the stretch to rupture the line circuit receiving coded current at the end of the stretch entered by the train to establish the stop condition of the opposing wayside signal and to discontinue the supply of coded current to the track for governing cab signals of opposing trains. 50

8. An absolute permissive block signal system for railways including, a stretch of single track 75

- between two passing sidings, a wayside signal at each passing siding to govern traffic in opposite directions through the stretch and each having an absolute and a permissive condition, a line circuit associated with each wayside signal said line circuit normally supplied with coded alternating current at the end of the stretch remote from the signal with which said line circuit is associated, a relay for each line circuit energized 5 in response to the coded current of the associated line circuit for holding in abeyance the absolute and permissive condition of the associated wayside signal, means associated with each line circuit to supply to the track of the stretch from the line circuit coded alternating current adapted to govern train-carried cab signals of trains travelling in the same direction as that governed by the associated wayside signal, a first trackway means responsive to a train entering either end 10 of the stretch to rupture the line circuit receiving coded current at the end of the stretch entered by the train to establish the stop condition of the opposing wayside signal and to discontinue the supply of coded current to the track for 15 governing cab signals of opposing trains, and a second trackway means responsive to a train entering either end of the stretch to establish the permissive condition of the wayside signal at the end entered by the train.
16. An absolute permissive signal system for railways including, a stretch of railway track, an eastbound wayside signal and a westbound wayside signal, an eastbound line circuit and a westbound line circuit, means at the east end of the stretch to supply to the eastbound line circuit current to govern the eastbound wayside signal and to supply to the traffic rails of the stretch a current adapted to control cab signals of eastbound trains, means at the west end of the stretch 20 to supply to the westbound line circuit current to govern the westbound wayside signal and to supply current to the traffic rails a current adapted to control cab signals of westbound trains, a first means responsive to a train entering the stretch at either end of the stretch to discontinue the supply of current to the opposing line circuit to thereby set the opposing wayside signal at 25 stop and leave the cab signals of opposing train without control, and a second means responsive to the train entering the stretch to establish a permissive condition of the wayside signal governing traffic moving in the same direction as that of the train entering the stretch.
17. Railway traffic controlling apparatus including, a stretch of railway arranged in track sections, a plurality of control circuits for normally supplying to the traffic rails of each of said track sections a traffic governing current, a tuned alternator for at times supplying current 30 to said control circuits, and a code transmitting means to code the current delivered by said alternator to said circuits and so arranged that the code impulses are delivered successively to the plurality of circuits in such an order that the maximum amplitude of the current delivered by the alternator is minimized.
18. In combination, a plurality of control circuits, a source of current adapted to actuate at times a tuned alternator, and a coding means to supply to each of said control circuits from said alternator periodic impulses of current so arranged that substantially one-half of said control circuits are supplied with an impulse at a time.
19. In combination, a plurality of control circuits, a source of current adapted to actuate at 35 times a tuned alternator, and a coding means to supply to each of said control circuits from said alternator periodic impulses of current so arranged that the "on" period of an impulse for substantially one-half of said control circuits occurs during the "off" period of the impulse for the other half of said control circuits.
20. In combination, a stretch of railway, a wayside signal to govern traffic through said stretch, a track circuit for the stretch adapted to control train-carried cab signals, a transmission line to supply alternating current of a given frequency, a traffic controlled line circuit, means for normally furnishing coded alternating current from said transmission line to said line circuit, means responsive to the coded alternating current of the line circuit to control said wayside signal and to supply coded alternating current to said track circuit, a normally inactive local source of alternating current of the same frequency as that of the transmission line, and means to render the local source active and to transfer the line circuit from the transmission line to the local source upon an interruption of the supply from the transmission line.
21. Railway traffic controlling apparatus including a stretch of railway arranged into a plurality of track sections, a track circuit for each section, a tuned alternator associated with said stretch for at times supplying alternating current to the track circuits, a coding means to code the current delivered by said alternator which means includes two code contacts alternately closed and so arranged that substantially an equal number of track circuits are supplied through each of said code contacts.
22. In combination, a source of direct current, a tuned alternator for supplying alternating current from said direct current source to a pair of control circuits, coding means having a coding contact associated with each control circuit for coding the current delivered by said tuned alternator to said control circuits and so arranged that only one contact is closed at a time to thereby minimize the maximum amplitude of the alternating current to be delivered by said alternator.
23. In combination, a plurality of control circuits, a source of direct current, a vibrating member and a transformer arranged to convert the direct current from said source into alternating current, circuit means to deliver said alternating current to said control circuits, and a coding device to code the alternating current and having a plurality of code contacts that are successively closed and so arranged that substantially an equal number of control circuits are supplied through each code contact to thereby minimize the maximum amplitude of the alternating current.
24. In combination, a stretch of railway arranged into a plurality of track sections, a track circuit for each section adapted to control train-carried cab signals, a transmission line adapted to supply alternating current of a given frequency, a normally inactive tuned alternator adapted to develop alternating current of the same frequency as that of the transmission line, circuit means including a pair of coding contacts alternately closed to normally furnish coded alternating current from the transmission line to said track circuits and arranged that substantially an equal number of track circuits are supplied through each code contact, and means to automatically render the tuned alternator active.

and to transfer the circuit means from the transmission line to the tuned alternator upon an interruption of the supply from the transmission line.

- 5 18. In combination, a stretch of railway, a wayside signal to govern traffic through the stretch, a direct current relay to govern the operation of the signal, a track circuit including the traffic rails of the stretch, traffic controlled
10 means adapted to supply under certain conditions coded alternating current, rectifying means adapted to supply rectified current from the traffic controlled means to said relay to govern said signal, and a transformer to supply
15 from the traffic controlled means to the track circuit coded alternating current adapted to influence train-carried cab signals.

19. In combination, a stretch of railway arranged into a plurality of track sections, a wayside signal for governing traffic through said stretch, a line relay for controlling the operation of said signal, a track circuit for each of said track sections adapted to influence vehicle carried train control apparatus, and a traffic controlled line circuit for controlling said line relay and energizing said track circuits.

20. In combination, a stretch of railway, a wayside signal for governing traffic through said stretch, a track circuit for said stretch adapted
25 to control vehicle-carried train control apparatus, a line circuit, means governed in accordance with traffic conditions for supplying said line circuit with current, means controlled by the line circuit and responsive to said current for controlling
30 said signal, and means for supplying current from the line circuit to said track circuit.

- 35 21. Railway traffic controlling apparatus including, a stretch of railway over which traffic may move in one or the other direction, a first

and a second traffic governing device for governing traffic through the stretch in said one and said other direction respectively, two line circuits one for each of said devices for governing the device associated therewith and for supplying current to the rails of said stretch for governing vehicle-carried train control apparatus, and means for selectively energizing said line circuits.

5 22. The method of controlling traffic through a given stretch of railway track by means of both a wayside signal and cab signals, which comprises supplying current to a line circuit extending through said stretch, and using said current to control a line relay which governs the 15 wayside signal as well as to furnish the trackway energy for controlling said cab signals.

23. In an absolute permissive block signal system, the method of controlling opposing traffic movements in a given stretch of track by means of both wayside and cab signals, which comprises supplying current selectively to one or another of two line circuits in accordance with the direction established by traffic entering the stretch, and using said current to control the 25 wayside signal governing traffic movements opposed to said established direction and to furnish the trackway energy for controlling said cab signals.

24. In combination, a stretch of railway arranged into a plurality of track sections, a wayside signal for governing traffic through said stretch, a line relay for controlling the operation of said signal, a track circuit for each of said track sections adapted to influence vehicle-carried train control apparatus, and a line circuit controlled by said track circuits for governing said line relay and energizing said track circuits.

CHARLES W. FAILOR.
